LOUVERED AWNING

Orman O. McKinley, Indianapolis, Ind.

Application May 3, 1946, Serial No. 667,164

3 Claims. (Cl. 20—57.5)

1

The present invention relates to a louvered awning, and is particularly concerned with the provision of an extremely simple and inexpensive structure of the class described, particularly adapted to be made of metal or other stiff but workable sheet material. The primary object of the invention is to provide a structure having the characteristics above-described which shall be relatively light, readily assemblable in any desired length and width, adapted to be hung for swinging movement about a horizontal axis at the top of a window frame, and adapted for ready and inexpensive repair or replacement of individual parts. A further object of the invention is to provide, for use with a device of the character described, simple but effective means for adjusting the position of the structure about its hinged axis. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a front elevation of an awning constructed in accordance with my invention and associated with a window frame;

Fig. 2 is an end elevation thereof;

Fig. 3 is an enlarged fragmental elevation of the upper portion of an awning constructed in accordance with my invention, and showing a fragmental section of the supporting wall therefor;

Fig. 4 is a broken perspective view of a fragment of my awning; and

Fig. 5 is an enlarged horizontal section showing a detail.

Referring more particularly to the drawings, it will be seen that I have illustrated an awning, indicated generally by the reference numeral 10, supported in association with a window frame 11. A preferred form of support for my awning comprises a pair of hooks 12 secured to, and projecting from the window frame 11 in a common horizontal plane, each of said hooks being formed with a mouth 13 which opens upwardly and inwardly toward the supporting frame 11.

A pair of bars 14 and 15 are preferably connected, at their upper ends, by a stretcher bar 16 which is adapted to be received in the hooks 12 to provide a hinged mounting about which the awning may swing.

2

The bars 14 and 15 are identical, but allochirally arranged; and therefore only one such bar is illustrated in detail. As is clearly shown in Fig. 4, the bar 14 is of channel construction, comprising a web 17 flanked by flanges 18 and 19.

Upon the bar 14 is mounted a series of brackets, indicated generally by the reference numeral 20. Each bracket comprises an integral piece of sheet metal, of comparable stiff but workable sheet material. One straight edge portion of the bracket is turned, substantially at right angles out of the general plane of the bracket, as at 21, and is then rebent upon itself, as at 22, to form a channel 23 opening toward the web 17. Another edge portion 24 of the sheet, disposed at an acute angle to the first-mentioned edge of the sheet, is likewise turned at right angles out of the general plane of the sheet. A tongue 25 is punched out of the body sheet, in a region intermediate the two above-described edges, and turned substantially at right angles out of the general plane of the sheet, and is then rebent upon itself, as at 26, to form a channel opening toward the web 17. A further portion 28 of the sheet is cut loose from the sheet body, in a region below the tongue 25, leaving a connecting bar 27 between the edges 21 and 24, and said portion 28 is turned substantially at right angles out of the general plane of the sheet, into coplanar relation with the tongue 25. Said portion 28 is then rebent upon itself, as at 29, to provide a channel opening toward the web 17.

As will be readily perceived upon inspection of Fig. 4, the bracket 20 may be slidably positioned upon the bar 14, the channel 23 receiving the bar flange 18, and the channels formed by the tongue 25 and the portion 28 receiving the bar flange 19. The construction of the bracket is such that the edge 24 now lies in a plane acutely angularly related to the bar flange 19, and meeting said flange in a horizontal line.

Each bracket 20 on the bar 14 has an allochirally arranged mate upon the bar 15, the edge portion 24 of each bracket lying in a common plane with the corresponding portion of its mate upon the other bar. Extending between, and fixed to, such inclined edge portions of each pair of brackets is a slat 30 which may be formed of sheet metal or of any similar stiff but workable sheet material, each such slat preferably being formed, at its upper edge to provide an upwardly and forwardly turned flange 31, and being formed at its lower edge to provide a downwardly turned flange 32. The flange 31 of each slat (save the uppermost slat) overlaps the lower

portion of the immediately superjacent bracket, as is clearly to be seen from Fig. 3; and the flange 32 of each slat depends below the level of the upper edge of the flange 31 of the next subjacent slat.

A slat 30' is associated with the topmost brackets of the two bars; and it, too, is formed at its upper edge with an upwardly and forwardly turned flange 31', and at its lower edge with a downturned flange 32'.

The hooks 12 are so positioned that, when the stretcher bar 16 is supported therein, the edge portions 21 of the brackets mounted on the bars 14 and 15 are spaced from the wall 11 a distance slightly greater than the horizontal distance between the bases of the hooks 12 and the mouths 13 thereof. Because of this arrangement the awning may be dismounted from the hooks by an upward and inward movement thereof, whereby the bar 16 is carried out through the mouths of the hooks, the bars 14 and 15 being thereby moved substantially into contact with the wall 11.

Because of this necessary spacing of the bars 14 and 15 from the wall, the flange 31' is preferably so arranged as to be moved substantially into contact with the wall 11 when the bottom of the awning is swung outwardly.

A bracket 33 is secured to the window frame 11, at a point below the hooks 12, and provides a pivotal mounting for a lever 34. Said lever is provided, at its outer end, with a portion 35 located substantially in engagement with the web 17 of the bar 14; and said lever carries a hook 36 adapted to embrace the flange 18 of said bar 14. Said hook projects through a suitable opening in the lever 34, and carries a wing nut 37, whereby said hook may be tightened into clamping engagement with the bar 14. Obviously, the parts are shown, in Fig. 2 with the lever 34 holding the lower end of the awning outwardly substantially to its limit of movement; and it will be clear that, upon loosening of the wing nut 37, the lever 34 may be swung in either direction about its pivotal mounting on the bracket 33 to adjust the angular position of the awning 10 with respect to the window frame.

I claim as my invention:

1 A louvered awning comprising a pair of 50

parallel bars, a series of brackets for one bar, each bracket comprising an integral sheet metal piece having a portion embracing its bar and a portion angularly inclined downwardly and away from its bar, a corresponding series of brackets for the other bar, each comprising an integral sheet metal piece having a portion embracing its bar and a portion angularly inclined downwardly and away from its bar, said inclined portion of each bracket being coplanar with the corresponding portion of a mating bracket in the other series, and a slat extending between and secured to said inclined portion of each mating pair of brackets.

2. For use in an awning, a bracket comprising an integral sheet, one straight edge of said sheet being turned substantially at right angles out of the plane of said sheet, another edge of said sheet, inclined at an acute angle to said first-named edge, being turned substantially at right angles out of the plane of said sheet, and a portion of the body of said sheet intermediate said edges being turned substantially at right angles out of the plane of said sheet into substantial parallelism with said first-named turned edge, but leaving an integral bar joining said edges.

3. The bracket of claim 2 in which the substantially parallel turned portions are inwardly rebent upon themselves to provide substantially parallel channels opening toward the plane of said sheet.

ORMAN O. MCKINLEY.
